UNITED STATES PATENT OFFICE.

JOHN B. JOHNSON, OF LAUREL, SOUTH DAKOTA.

INSULATING-BUSHING.

1,189,960.

Specification of Letters Patent.

Patented July 4, 1916.

Application filed April 30, 1914. Serial No. 835,517.

To all whom it may concern:

Be it known that I, JOHN B. JOHNSON, a citizen of the United States, residing at Laurel, in the county of Sully and State of

- 5 South Dakota, have invented certain new and useful Improvements in Insulating-Bushings, of which the following is a specification, reference being had therein to the accompanying drawing.
- 10 This invention relates to an insulating bushing and has special reference to a device which is adapted to form a tube through which an electric cable may be passed when it is desired to allow a cable to pass into
- 15 a house or other structure.

Another object of this invention is the production of an insulating bushing which is formed to facilitate the passing of an electric cable into a house, this bushing being 20 provided with a protecting hood upon its outer end for preventing the weather from beating through the tube or pipe, this pipe being inclined to allow any moisture which may be contained therein to run so as to to 25 be expelled from the outer end thereof.

With these and other objects in view this invention consists of certain novel combinations, constructions and arrangements of parts as will be hereinafter fully described

30 and claimed.

In the accompanying drawing: Figure 1 is a longitudinal section taken through the insulating bushing showing the same in use. Fig. 2 is a detailed perspective view of the 35 insulating bushing. Fig. 3 is a section taken on the line 3—3 of Fig. 1 looking in direction of the arrows.

Referring to the accompanying drawing by numerals 1 designates the wall of a house 40 in which there is formed an inclined passage 2. The tube or pipe of the insulating bushing is adapted to be positioned within this passage 2 for allowing the electric cable to be passed into the house. The insulating 45 bushing comprises an elongated tube or pipe 3 having a central bore 4 formed therein. A hood is integrally formed upon the outer end of this tube 3 and comprises a back 5 having integral sides 6. The upper portion 50 is covered by the curved top 7 which is curved downwardly toward its outer portion for shedding water and allowing the same to dry easily. The ears 8 having central apertures 9 are formed integrally upon the 55 rear portions of the sides 6 for the purpose

of allowing the securing means to be passed therethrough for holding the hood in engagement with the wall thereby retaining the insulating bushing upon the wall.

By carefully referring to Fig. 1 it will 60 be seen that the tube 3 extends at an acute angle to the upper portion of the back 5 of the hood and at an oblique angle to the lower portion of the hood thereby causing the pipe or tube 3 to slant upwardly. The 65 outer end of the pipe or tube 3 extends for a spaced distance beyond the outer face of the back 5 and the back 5 is provided with a thickened body 6 which extends upwardly to terminate evenly with the outer end of 70 the tube or pipe 3.

When this device is in use the pipe or tube 3 is positioned within the passage 2 formed in the wall 1 so as to extend entirely therethrough. The back 5 will then 75 abut against the outer surface of the wall 7 and will be secured thereto by a suitable means to be passed through the ears 8. The electric cable 10 is then extended upwardly into the interior of the hood, the end of the 80 cable will of course strike upon the back 5 and may be moved until it strikes upon the thickened curved portion 5' of the back. This thickened curved portion 5' will constitute a guide for allowing the end of the 85 cable to slide thereon and as soon as the cable slides thereon it will drop or be guided into the outer end of the tube 3. Then by forcing the cable along it will pass through this tube 3 and into the interior of the 90 house. In this manner it will be seen that the cable may be safely passed into the house without causing any short circuit while the weather will be kept from beating into the insulating bushing, owing to the fact that 95 the hood will provide the outer end of the tube 3 with a protector means, while the inclined construction of the tube 3 will cause any moisture which may happen to be contained therein to run outwardly to the outer 100 end of the tube where it will be discharged.

This insulating bushing is preferably made of porcelain for withstanding rough usage, but it will, of course, be obvious that the same may be formed of glass, rubber, or 105 any suitable insulating material which is desirable to be used.

From the foregoing description it will be seen that a simple and efficient insulating bushing has been produced which will facili- 110

tate the passing of electric cables into a building and which is so formed as to be cheaply constructed and operate efficiently.

I claim:

5 An insulating bushing comprising a tube, a hood formed integral upon the outer end of said tube and open at the bottom, said hood provided with a rear wall extending vertically upward from said open bottom
10 having a thickened curved portion adjacent

the outer end of said tube, said thickened curved portion terminating evenly with the outer end of said tube.

In testimony whereof I hereunto affix my signature in presence of two witnesses.

JOHN B. JOHNSON.
